(57) **CLAIM**

The ornamental design for a sanding nozzle, as shown and described.

DESCRIPTION

FIG. 1 is a front perspective view of a sanding nozzle showing my new design;

FIG. 2 is a left side elevational view, the right side being a mirror image;

FIG. 3 is a front elevational view;

FIG. 4 is a top plan view, the bottom plan view being a mirror image; and,

FIG. 5 is a rear elevational view.

The broken lines depict unclaimed environmental subject matter, which form no part of the claimed design.
